(57) **CLAIM**

The ornamental design for a cell culture module, as shown and described.

DESCRIPTION

FIG. 1 is a perspective view of a cell culture module showing my new design;

FIG. 2 is a top view;

FIG. 3 is a side view;

FIG. 4 is a view from the bottom.

FIG. 5 is a perspective view of the cell culture module when pushed together showing my new design;

FIG. 6 is a top view;

FIG. 7 is a side view; and,

FIG. 8 is a view from the bottom.
